UNITED STATES PATENT OFFICE.

CHARLES D. LYON, OF CHICAGO, ILLINOIS.

WEATHER STRIP.

Application filed April 9, 1923. Serial No. 630,901.

To all whom it may concern:

Be it known that I, CHARLES D. LYON, a citizen of the United States, residing at Chicago, in the county of Cook and State of Illinois, have invented new and useful Improvements in Weather Strips, of which the following is a specification.

This invention relates to a weather strip for use upon windows, doors or similar articles to keep out the weather and the primary object of the invention is to simplify the construction of a weather strip while at the same time assure tight connection between the movable and stationary strips.

An object of the invention is the construction of a strip that may be quickly arranged in place and will have yieldable engagement with the door or sash so as to compensate any inequalities in the fit between the window and its frame or door and its frame.

A feature of the invention is the construction of a strip in such a manner that same is of a universal type so as to be used for various constructions of windows as well as doors without in any way changing same.

With these and other objects in view the invention will be better understood from the following detailed description taken in connection with the accompanying drawing wherein:

Fig. 1 is a sectional view through a window sash and its frame showing my improved strip applied thereto.

Fig. 2 is an enlarged end elevation of the strip.

Fig. 3 is a fragmentary side elevation of one end of the strip.

Again referring to the drawing illustrating one of the many constructions of my invention the numeral 1 designates what will be known as the stationary limb which lies in flat contact with that portion of the window frame B directly opposite the sash C. This limb 1 has a flange extension 2 that is secured to the exposed portion of the frame by screws or notches 2'. The movable limb 3 extends at an incline to the limb 1 and is connected to the limb 1 by the bead 4. The limb 3, at its juncture with the bead

4, is provided with a crimp 5 which besides stiffening the construction more evenly distributes the strain to which the bead 4 is subject and permits yieldable movement of the limb 3 towards and away from the limb 1. A flange 6 formed as a continuation of limb 3 extends in a direction to have slideable movement over the flange 2. By referring to the drawing it will be seen that the strip is formed from sheet metal having proper resiliency and with the various parts shaped and constructed as shown a maximum amount of resiliency is accomplished while at the same time distortion of the parts in the active operation of the strips is practically eliminated.

It will also be noted the construction is such that the strip may be very readily inserted into the limited space between the sash and its frame.

It will also be noted the construction and operation of the parts are such that window sash having other movement than the ordinary sliding sash may be accommodated and besides the strip may be readily associated with doors without in any way changing the shape or construction thereof.

It is, of course, to be understood the invention may be constructed in various other manners and the parts associated in different relations and therefore, I do not desire to be limited in any manner except as set forth in the claims hereunto appended.

Having thus described my invention what I claim is:

1. A weather strip for windows comprising a stationary limb, a movable limb yieldably connected to the first limb, a flange on each limb for sliding engagement with each other, one of the flanges being arranged for permanent attachment to a suitable support.

2. In combination with sash and frame a weather strip formed from sheet metal and having a stationary limb lying in flat engagement with the frame opposite the sash and a flange lying flat against an exposed portion of the frame and secured thereto, a bead forming a continuation of the stationary limb, a crimp forming a continuation of the bead, a movable strip forming a continu-

ation of the crimp, and a flange forming a continuation of the movable limb and slidably engaging said first mentioned flange.

3. In combination with a sash and frame a weather strip formed from sheet metal having a yieldable action between the sash and frame and including a pair of flanges

one fixed to the frame and the other sliding over the first mentioned flange, said flanges arranged to extend at right angles to the sash to be exposed to view.

In testimony whereof I affix my signature.

CHARLES D. LYON.
